UNITED STATES PATENT OFFICE

CARL A. LARSEN, OF OAK PARK, ILLINOIS

HOOD FOR AUTOMOBILE ENGINES

Application filed August 9, 1928. Serial No. 298,464.

My invention relates to the hoods of automobile engines, and the object thereof is to provide means for controlling the currents of air through the hood so as to aid in the proper establishment of heat control at different seasons of the year for the comfort of the passengers and for efficiency in operation.

The principles of my invention are illustrated in the drawings, in which:

Figure 1 represents the hood of a motor car in longitudinal section, looked at inwardly from the right side of the car and exhibiting my device as applied to the inner left-hand side;

Fig. 2 represents a section on the dotted line 2—2 of Fig. 1;

Fig. 3 represents an enlarged face view of a portion of Fig. 1; and

Fig. 4 represents a section on the dotted line 4—4 of Fig. 1.

Further describing my invention with reference to the drawings in which like characters of reference denote like parts throughout:

Numerals 1 represents the main body portion of an automobile, 2 represents the hood in central longitudinal section, and 3 is the radiator thereof, while 4 is the upper part and 5 is the far side of an automobile hood looked at from the inside. Numerals 6, 6 represent the wings of a centrally disposed cooling fan 7 adapted to impel its own self-created air currents, as well as those relatively created by the moving vehicle, and passing through the radiator 3, over the motor throughout the hood. In the side wall 5 are a number of openings 8 formed by cutting through the material of the side wall on one edge and leaving pushed out portions 9, whereby a partially protected air opening is provided at the rear thereof creating a partial suction which aids in cooling the engine and scavenging the heated and foul air within the hood.

The vertical openings, indicated in Fig. 4, extending practically transversely up and down across a considerable portion of the metal sheet from which the sides of the hood are formed, are provided with adjustable

shutters adapted to close thereover or alternately adapted to be opened or closed with reference thereto, as desired. A multiplicity of such shutters is provided and designated by the letters *a* to *h*, inclusive. These shutters may be mounted directly on the side walls of the hood, or I may provide a rectangular frame-work 10 as a mounting for the said shutters which may be secured to the inner side walls of the hood by means of bolts or rivets 11. A suitable structure for the said rectangular frame-work may consist of the angle bars having body portion 12 and rectangular flanges 13, which are secured to the upper portion of the side wall 5, while similar bars 12' and 13' in inverse position may become the lower portion of the frame-work. It will be seen that the horizontal longitudinal bars of the frame-work will act as supports for the hinged shutters while they are connected into a rigid structure by means of the vertical end bars 14.

Between the upper and lower ends of the shutters and the corresponding upper and lower flanges are mounted washers 18 and springs 19 held therebetween, thereby forming an elastic and noiseless fastening. In order that the shutters thus mounted, may have uniform control for fastening in the final operative position, as desired, I provide draw rod 20 having properly spaced openings to fit over and receive the offset cranks 17 on the rods 15. An offset flange 21 is provided on the element 10 on which the extended portion 20' of the draw rod rests. Such extension 20' and the flange 21 are provided with corresponding openings so that, when the shutters are placed in proper desired position, they may be held rigidly therein by means of a cotter pin 22 or similar device.

It should be observed that the apparatus above described is adapted to be used differently in different conditions of the atmosphere. When the car is being operated in high summer heat, the air which is forced through the radiator by the movement of the car and assisted backward by the movement of the fan is forced past the hot motor and then against the dash and floor-boards of the

car and finally escapes at the back and under the floor of the car, only a small part thereof escaping on the way back. But when the shutters are open, they will intercept this 5 current of hot air and cause it to go out through the side openings, thus keeping this hot air from the dash and floor-boards and pedal openings in the floor-boards, relieving 10 discomfort to passengers. This speedy egress 15 of the heated air will also tend to assist in cooling all parts enclosed under the hood; such shutters being adjustable as necessary.

In cool weather or in winter, the shutters will be tightly closed so that a large amount 15 of the hot air will be retained, little thereof escaping through the sides, while practically no cold air is admitted from the outside to interfere with the correct temperature of the 20 motor.

25 The air coming through the radiator and forced back by the fan past the motor and against the dash and floor-boards creates a temperature which will be comfortable for the passengers when the weather is cold.

25 Having thus described my invention, and the application thereof so that it can be constructed and applied by those skilled in the art, I claim:—

1. In an engine having an enclosing hood 20 with external openings, integrally formed air deflectors opening backwardly from the hood, shutters hinged inside the hood and opening forwardly to receive air currents from the radiator and deflect them through 35 said external air openings.

2. In an engine having an enclosing hood with external openings, air deflectors integrally formed with said hood opening backwardly therefrom, shutters hinged inside the 40 hood and adapted alternately to close said external openings or to open them so as to receive air currents and deflect them outwardly through said external air openings said shutters having a longitudinal edge thereof 45 pivotally secured to the rear side of said external openings.

3. In a motor hood having external air openings in the sides thereof adapted to normally discharge air currents backwardly 50 from a moving car, shutters pivotally secured to the sides of the hood on the inside thereof whereby the pivot points of each of the shutters may be placed in close relation to the rear edge of the external air openings, means for 55 alternately so placing said shutters as to impede the air flow from the external openings or to receive heated air currents from the fan and direct them through the external air openings, and means for causing partial rotation of the shutters whereby the same may be presented in the direction in which the vehicle 60 is travelling.

4. In an automobile hood having external air discharge openings on the sides thereof, a 65 plurality of flanges inside the hood extending

above and below the said air discharge openings substantially parallel to each other, crank rods journalled in each of the equally spaced parallel openings in the inset flanges, shutters having one of their longitudinal 70 edges rigidly secured to the crank rods, whereby the shutters may extend in the direction of the cooling fan and in the direction of travel of the motor vehicle, a pull bar having equally spaced openings in which the said 75 cranks are received, and means for locking the pull bar to hold the shutters in any desired adjusted position relatively to the air discharge openings.

5. In an automobile hood having a multiplicity of air discharge openings on the sides thereof, louvres mounted over the openings extending in the direction of the stream line of the motor vehicle, whereby air may be caused to be drawn through the louvres upon 80 movement of the vehicle, a multiplicity of shutters pivotally attached to the inside of the hood adjacent to the air discharge openings, said shutters having a longitudinal edge 85 pivotally secured to the side of the hood adjacent to the louvres, means for causing partial rotation of the shutters whereby the shutters may be caused to extend in the direction of the cooling fan of the automobile or in 90 parallel relation with the side of the automobile hood, and means for holding the shutters in an adjusted position.

6. A motor hood having a series of vertical slits along the sides thereof and a series of 100 adjustable shutters arranged behind said slits, said shutters being pivotally supported at one edge, and a bar attached to each of the shutters on a given side of the hood, said shutters adapted to be opened and closed by the movement of said bar.

7. A motor hood having a series of vertical slits along the sides thereof, an outwardly and backwardly extending air deflector on the front side of each slit, shutters mounted behind said vertical slits and pivotally attached to the hood by the rear vertical edges of said shutters, and a bar on each side of the hood attached to all shutters on that side whereby the shutters on either side of the hood may be opened or closed independently 110 of those on the other side.

In witness whereof, I have hereunto set my hand at Chicago, Illinois, this 3rd day of August, 1928.

CARL A. LARSEN. 115
